UNITED STATES PATENT OFFICE.

JOHN J. LEARY, OF BROOKLYN, NEW YORK.

PRINTING MACHINE.

Application filed September 19, 1923. Serial No. 663,541.

This invention relates to printing machines of the type known as web and flat bed perfecting presses. In these types of presses wherein the paper is printed successively upon the opposite sides, it is necessary to pass the ink-wet side of the web or paper in contact with a packing cylinder, with the result that the packing cylinder receives a quantity of ink and other matter, together known as offset deposit, from the paper. If the deposit were not removed from the packing cylinder it would collect or accumulate and smut or smudge the web of paper, and attempts heretofore made to remove this deposit have not brought entirely satisfactory results.

An object of this invention is to provide improved means for removing the offset deposit from the second packing cylinder in a simple and effective manner; and which will be simple, relatively inexpensive and capable of application to existing types of presses without material modifications or changes therein. Other objects and advantages will be apparent from the following description of an embodiment of the invention and the novel features will be particularly pointed out hereinafter in claims.

In the accompanying drawing:

Fig. 1 is a diagram illustrating the application of the invention to a printing press of the web perfecting type;

Fig. 2 is an elevation of the cleaner cylinder which forms an essential part of the invention; and

Fig. 3 is another elevation of the cleaner cylinder with the doctor blade in operative relation thereto.

In the illustrated embodiment of the invention and referring to Figure 1, the web or paper which is to be printed is conducted from the supply roll 1 over suitable guiding rolls 2, and then between the first plate cylinder 4 and the first packing cylinder 5 where it is printed upon one side. The web or paper is then conducted over suitable guiding rolls 6 and between a second plate cylinder 7 and a second packing cylinder 8, where it is printed upon the opposite side, the ink-wet side of the paper or web during the second printing operation running in contact with the surface of the second packing cylinder and leaving thereon what is known as an offset deposit. The web or paper is then conducted over suitable rollers

9 to a cutting or folding machine, not shown.

The invention is particularly directed to the removal of the offset deposit from this second packing cylinder 8. For this purpose a cleaning cylinder 10 is mounted for rotation about its longitudinal axis with its peripheral surface in contact with the surface of the second packing cylinder 8. This cylinder 10 is geared for operation either in the same direction as, or in the opposite direction to, the rotation of the packing cylinder 8 at their line of contact. Preferably the direction of rotation of the cleaning cylinder will be opposite to that of the packing cylinder at their line of contact.

The cleaning cylinder 10 is illustrated in detail in Figure 2, and is provided upon its peripheral surface with cleaning strips extending longitudinally thereof, which are spaced apart peripherally of the cylinder so as to leave spaces or grooves 12 between them. The cleaning strips are preferably mounted upon the cylinder, with a progression peripherally as well as longitudinally of the cleaning cylinder, so that the strips and the spaces between them will act somewhat as a spiral conveyor for conveying the deposit removed from the packing cylinder to the ends of the cleaning cylinder. In order to accelerate the passage of the removed deposit from the cleaning cylinder, the strips may be laid in a spiral manner around the surface of the cleaning cylinder from an intermediate point so that the removed offset deposit will be conveyed in both directions towards the ends of the cleaning cylinder.

A doctor blade 13 is suitably mounted at one side of the cleaning cylinder with an edge in scraping relation with the outer surface of the cleaning strips 11 so as to remove therefrom a large proportion of the collected offset deposit. This doctor blade, at its scraping edge, is preferably inclined toward each end from an intermediate point, with the scraping edge suitably formed so as to allow the doctor blade to engage the cleaning cylinder for its entire length. With the doctor blade inclined toward each end, the collected deposit which is removed thereby from the cleaning cylinder will be more readily conducted to the ends, at which the deposit may be collected or discharged into suitable cups or containers. It will be

understood that the doctor blade may be inclined only in one direction from end to end and operated very satisfactorily, but operates in a more satisfactory manner by having it inclined toward opposite ends from an intermediate point for the reason that the removed deposit is more rapidly discharged when it travels less than a half of the length of the cylinder rather than nearly the entire length thereof.

In order to prevent the permanent adherence of the ink, contained in the offset deposit, to the cleaning strips 11 of the cleaning cylinder, I may provide an oil fed roller 14 in contact with the cleaning cylinder for oiling the strips during their rotation and prior to their contact with the second packing cylinder. The oil feeding roller 14 may be continuously supplied with oil by any suitable means such as by an oil fountain 15.

The cleaning cylinder may be constructed of any suitable material, and may, for example, be given a surface of wood with strips of suitable cleaning material secured thereon. The cleaning strips may be of various suitable materials such as, for example, plush, carpet, bristles, fabric and vitrified rubber. The doctor blade may be of any suitable material, such as metal, wood, or composition.

To facilitate or assist in the removal of the offset deposit from the second packing cylinder, this cylinder is preferably provided with a peripheral cover or top sheet 16, formed of or treated with, a material which has little or no affinity for printer's ink. For example, a special grade of suitable paper ranging from 6 to 15 points thick may be used as the cover or top sheet of the second packing cylinder, and this paper is prepared or treated to repel or be non-absorbent as to printer's ink. The cleaning cylinder, acting against such a cover or top sheet on the second packing cylinder, may thus more effectively clean the surface of the packing cylinder.

In the operation of the cleaning device, and assuming that the cleaning cylinder is driven in a direction to carry its surface oppositely to the surface of the second packing cylinder at their line of contact, the cleaning strips will act very much as brushes in sweeping or wiping the offset deposit from the packing cylinder, a portion of the removed deposit being promptly removed from the cleaning cylinder by the doctor blade, and the remainder being progressively carried, by the spiral grooves between the strips endwise of the cleaning cylinder until it is discharged from the ends thereof. The oil feeding roller serves to oil the strips sufficiently to prevent the permanent adherence thereto of the printing ink and deposit. With this method of cleaning the second packing cylinder, the use of the

objectionable smut or offset roll is unnecessary, and the press may be satisfactorily operated continuously for long periods of time.

It will be obvious that various changes in the details and arrangements of parts, herein described and illustrated for the purpose of explaining the nature of the invention, may be made by those skilled in the art within the principle and scope of the invention as expressed in the appended claims.

Claims:

1. In printing machines having printing and packing cylinders, a cleaner for the packing cylinder comprising a cylinder contacting therewith and rotating in conjunction therewith, said cleaning cylinder having on its contacting surface a plurality of cleaning strips extending in a direction lengthwise thereof and peripherally spaced, 80 said strips being helically disposed from the center toward each end of the cleaning cylinder whereby the offset deposit which is removed from the packing cylinder by the strips will be progressively carried to the 90 ends of the cleaning cylinder and discharged.

2. In printing machines having second printing and packing cylinders, a cleaner for the second packing cylinder comprising a cylinder contacting therewith and rotating 95 in conjunction therewith, said cleaning cylinder having on its contacting surface a plurality of cleaning strips extending in a direction lengthwise thereof and peripherally spaced and means for oiling the strips on the 100 cleaning cylinder to prevent the adherence thereto of the offset deposit.

3. In printing machines having second printing and packing cylinders, a cleaner for the second packing cylinder comprising 105 a cylinder contacting therewith and rotating in conjunction therewith, said cleaning cylinder having on its contacting surface a plurality of cleaning strips extending in a direction lengthwise thereof and peripherally spaced and a doctor blade for removing the offset deposit from the outer surface of the strips.

4. In printing machines having second printing and packing cylinders, a cleaner for the second packing cylinder comprising 115 a cylinder contacting therewith and rotating in conjunction therewith, said cleaning cylinder having on its contacting surface a plurality of cleaning strips extending in a direction lengthwise thereof and peripherally spaced and a doctor blade for removing the offset deposit from the outer surface of the strips, the surface of said blade being inclined endwise to facilitate the discharge 120 therefrom of the removed offset deposit.

5. In printing machines having second printing and packing cylinders, a cleaner for the second packing cylinder comprising 125 a cylinder contacting therewith and rotating

at a different speed of rotation relatively to the packing cylinder, said cleaning cylinder having on its contacting surface a plurality of cleaning strips extending in a direction substantially lengthwise thereof and peripherally spaced, said strips being helically disposed from the center toward each end of the cleaning cylinder whereby the offset

deposit which is removed from the second packing cylinder by the strips will be ¹⁰ progressively carried to the ends of the cleaning cylinder and discharged.

In witness whereof, I hereunto subscribe my signature.

JOHN J. LEARY.
